UNITED STATES PATENT OFFICE

2,267,505

GARMENT

Stephen J. O'Bryan, Chicago, Ill., assignor to
O'Bryan Bros., Inc., a corporation of Illinois

Application September 19, 1940, Serial No. 357,464

1 Claim. (CL 2—73)

This invention relates to improvements in garments, and more especially an undergarment or slip adapted for wear by women.

Among the features of my invention is the provision of a combination brassière and slip.

Another feature of my invention is the making of such a garment that is very smooth on the inside, thus increasing the comfort of the wearer. This is accomplished by providing on the inside vertically continuous panels of cloth extending from the extreme lower edge of the skirt portion to the extreme upper edge of the brassière portion, thus eliminating all rough horizontal seams on the inside. Heretofore, in garments of this character, there was always present on the inside a more or less rough upstanding seam or crease in a substantially horizontal direction where the brassière portion joined the skirt portion of the garment. This is entirely eliminated in my improved garment.

By the use of such continuous panels on the inside of the garment the cost of the garment has also been greatly reduced without in any way impairing its wearing qualities. By the use of extra plies on the outside of the garment to form the brassière portion, it is suitably strengthened and reinforced.

If desired, my improved garment may be worn inside-out so that the smooth surface of the garment will be on the outside. When thus worn, the junction between the brassière portion and the skirt portion will hardly be visible through the outer garment. When thus worn, the continuous panels extending from the extreme bottom edge of the skirt portion to the extreme upper edge of the brassière portion will be on the outside in contact with the outer garment. The inturned edge of the brassière reinforcement will thus be on the inside of the garment and will show through the outer garment very slightly, or not at all.

Other features and advantages of my invention will appear more fully as I proceed with my specification.

In that form of device embodying the features of my invention shown in the accompanying drawings, Fig. 1 is a view in front elevation; Fig. 2 is a view taken as indicated by the line 2 of Fig. 1; Fig. 3 is a view taken as indicated by the line 3 of Fig. 1; Fig. 4 is a view similar to Fig. 1 showing the upper portion with a part of one of the brassière panels removed to show the construction; and Fig. 5 is a view of the upper portion of the garment in side elevation.

As shown in the drawings, the garment has an

upper brassière portion indicated in general by 10 and a lower dress or skirt portion indicated in general by 11, and is provided with the usual shoulder straps 12.

13 and 14 indicate vertical front and rear panels, respectively, and 15, 15 represent vertical side panels, each extending from the extreme lower edge of the skirt portion to the extreme upper edge of the brassière portion. These panels 10 are joined together in any suitable manner as, for example, by the vertical seams 16, 16. There is thus formed a tubular member adapted to encircle the body of the wearer extending the full length of the garment, that is from the top edge 15 of the brassière portion to the bottom edge of the skirt portion, said tubular member having only substantially vertical seams and being entirely free from horizontal seams.

17, 17 indicate outer front brassière panels and 20 18, 18 outer back brassière panels on the outside of the garment (as normally worn) adapted to encircle the bust of the wearer in the manner of a brassière. The front and rear panels extend around to the sides where they are joined by the 25 vertical seams 19, 19 under the arms; but at this point, they are preferably not joined to the vertical side panels 15, 15. The panels 17 and 18 are brought substantially to points in the front and back as indicated by 17a and 18a, respectively; and their lower edges are rounded downwardly from said points as indicated by 17b and 18b, respectively. The upper edges of the panels 17 and 18 are preferably pointed upwardly to some extent as indicated by 17c and 18c where 35 the shoulder straps are joined. The lower edges of the panels 17 and 18 are attached to the vertical panels 13, 14 and 15 by the seams 20, and their upper edges are joined to the upper edges of the vertical panels by the seams 21, as shown, 40 around the circumference of the garment.

It will be seen that when the garment is worn with the brassière panels 17 and 18 on the outside, the vertical panels 13, 14 and 15 will be next to the wearer and that these panels extend 45 continuously from the extreme upper edge of the garment to the extreme lower edge without any cross or horizontal folded edges, creases, or seams. At the seams 20 where the brassière panels 17 and 18 are joined to the vertical panels, the lower edges of the brassière panels 17 and 18 are turned inwardly as indicated by 17a and 18a (see Fig. 3); but these inturned edges lie outside of the vertical panels and consequently 50 are protected by the latter from giving discomfort to the wearer.

It is to be understood that the seams and folded edges as shown in Fig. 3 are greatly enlarged merely for the purpose of illustrating the manner of making the seams. The view is virtually a diagrammatic one.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as permissible, in view of the prior art.

What I claim as new, and desire to secure by Letters Patent, is:

A garment of the character described, including: a substantially tubular member adapted to

encircle the body of a wearer, said member formed of a plurality of vertical panels of sufficient length to form a brassière portion and a skirt portion, said vertical panels extending continuously from the upper edge of said brassière portion to the lower edge of said skirt portion; and a plurality of brassière panels attached by their upper and lower edges to one side of the brassière portion of said vertical panels, said brassière panels adapted to encircle the bust of the wearer, said brassière panels extending from substantially the center of the chest region downwardly around the sides of the bust toward the waistline under the armpits and thence around toward the center of the back, the ends of said panels terminating in slanting edges at the front and back to form a V neck at the front and back of the garment.

STEPHEN J. O'BRYAN.
